UNITED STATES PATENT OFFICE

HENRY B. SILVER, OF NEW YORK, N. Y.

BOTTLE-DIPPING MACHINE

Application filed June 24, 1927. Serial No. 201,206.

The present invention relates to means for capping bottles with a quick drying solution, the object being to provide mechanism by which a relatively large number of bottles 5 may be simultaneously and quickly capped or sealed, the mechanism being adjustable to various sizes of bottles and the solution-containing tank being readily removable and replaceable, so that solutions of various colors 10 can be substituted as desired.

In the accompanying drawings:

Figure 1 is a view partly in elevation and partly in section of the preferred embodiment of the invention,

15 Figure 2 is a sectional plan view on the line 2—2 of Figure 1,

Figure 3 is a vertical cross sectional view on the line 3—3 of Figure 2.

In the embodiment disclosed, a base 4 is 20 employed, on which are mounted standards. These standards, each consists of a lower tubular section 5 fixed upon the base and an inner rod section 6 slidably mounted in the tubular section. A contractile gripping collar 7, mounted on the section 6, rests upon 25 the upper end of the section 5 and serves to hold the section 6 at different elevations.

A reservoir supporting platform 8 is provided at its ends with brackets 9 slidably 30 mounted on the lower sections 5 of the standards and is adapted to be raised by a lever 9^a fulcrumed at 10 on the base 4. One arm 11 of the lever preferably carries at its free end a roller 12 that operates on a wear plate 13 on 35 the underside of the platform 8. The other arm 14 of the lever constitutes a handle for operating it. On this base is removably mounted a reservoir 15 that contains the solution into which the bottles are to be dipped, 40 and this reservoir may have a removable cover 16 provided with openings 17 through which the necks of the bottles pass. This is merely for the purpose of preventing undue evaporation. It will be understood that a 45 number of these containers are employed that can be placed upon and removed from the platform, and when removed and not in use, can be covered tightly by imperforate covers, not shown. The amount of movement of the 50 platform 8 and container 15 is determined by

stop collars 18 that can be clamped at any desired position on the lower or tubular sections 5 and are abutted against by the brackets 9 when the platform is elevated.

The rod sections 6 of the standards are 55 provided at their upper ends with supporting flanges 19, the rods projecting a short distance above said flanges and acting as anchors for removable bottle carrier plates 20 that have openings 21 that receive the upper ends of 60 the rod sections 6. Washers 22 may be located on the undersides of the flanges 19 to rest upon the clamps 7. These plates are each provided with means for supporting bottles in inverted position, and said means 65 preferably comprise sets of spring clips 23 secured to the under sides of the plates, and thus holding the bottles, as shown in Figures 1 and 3, in inverted position and in line with the openings 17 in the cover 16. 70

In using this apparatus, a reservoir 15 containing the desired solution is placed upon the platform and a bottle carrier plate supporting a set of bottles in inverted position 75 is placed upon the upper ends of the rod sections of the standards. The distance the necks of the bottles are to be immersed in the liquid is determined by vertically adjusting the rod sections 6 in the tubular sections 5 and stopping the elevation of the platform 8 at the desired height by the stop collars 18. After the parts are properly arranged, it will be evident that when a set of bottles 80 is in position it is only necessary to depress the handle arm 14, which will raise the platform 8 and the reservoir carried thereby until the necks of the inverted bottles are immersed, as indicated in Figure 2. Upon allowing the reservoir to again move downwardly, the coating will adhere to the bottle 85 necks and the entire set may then be removed by removing the carrier plate 20 and replacing it with another. 90

Obviously the mechanism disclosed provides for the use of the apparatus with bottles of various sizes and contours and one reservoir may be easily substituted for another, so that solutions of different colors and different consistencies may be readily employed. 95

In order to maintain a constant level of 100

the liquid in the reservoir a feeder may be employed, as shown in Figures 1 and 3. A supply funnel 24 is mounted on one side of the reservoir and has communication with its lower portion. The funnel is adapted to receive a bottle 25 containing a supply of the solution and as the level of the liquid in the reservoir drops, it will be augmented by that in the bottle, as will be obvious.

10 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

15 20 What I claim, is:

1. A bottle capping apparatus comprising a container for the capping solution, and having a top into which the neck of a bottle may enter, means for holding a bottle in inverted and suspended position above the container and at different heights, and means for elevating the container to cause the neck of the bottle to enter the top of the container and be immersed in the capping solution.

2. A bottle capping apparatus, comprising a container for the capping solution and having a top into which the neck of a bottle may enter, means for holding a bottle in inverted and suspended position above the container, means for elevating the container to cause the bottle neck to enter the container, means for limiting such relative movement to limit the depth of immersion of the neck in the solution, and means movable with the container for maintaining a constant level of the solution in the container.

3. In a bottle capping apparatus, the combination with a base, of standards thereon, a container vertically slidable on the standards, a bottle holder supported on the standards above the container and having means for suspending bottles in inverted position over the container in position to have their necks enter the container when the latter is elevated, means adjustable to different heights for limiting the amount of elevation of the container, and means for elevating the container to said limiting means when the latter is at different heights.

4. In a bottle capping apparatus, the combination with a base, of standards thereon, a container vertically slidable on the standards, means for elevating the container, and means for supporting bottles in inverted positions and at different elevations over the container in position to have their necks enter the container when the latter is elevated.

5. In a bottle capping apparatus, the combination with a base, of spaced extensible standards rising from the base and compris-

ing slidably telescoped upper and lower sections, a platform slidably mounted on the lower standard sections, means for elevating the platform, a container removably mounted on the platform, a carrier member detachably mounted on the upper standard sections, and bottle holders on the carrier member for holding a plurality of bottles in inverted positions with their depending necks in position to enter the containers when the same are elevated.

6. In a bottle capping apparatus, the combination with a support for a container for a capping solution, said support being capable of movement in an up and down direction, of vertically adjustable means for supporting bottles in inverted position over the movable support and in position to have their tops immersed in the solution thereby elevated.

7. In a bottle capping apparatus, the combination with a support for a container for a capping solution, said support being capable of movement in an up and down direction, of means for supporting bottles in inverted position over the movable support and in position to have their tops immersed in the solution thereby elevated, and vertically adjustable stop means in the path of the container support for limiting its vertical movement.

8. In a bottle capping apparatus, the combination with a support for a container for a capping solution, said support being capable of movement in an up and down direction, of means for holding bottles to be dipped in suspended position over the support, means for supporting said bottle holding means at different heights, stop means for varying the height to which the container support can be elevated, and means for elevating the container support to said different heights.

In testimony whereof, I affix my signature.

HENRY B. SILVER.
